UNITED STATES PATENT OFFICE.

CHARLES DISBENNET, OF LOGAN, OHIO.

INSULATOR.

1,260,160.

Specification of Letters Patent. Patented Mar. 19, 1918.

Application filed May 8, 1917. Serial No. 167,249.

To all whom it may concern:

Be it known that I, CHARLES DISBENNET, a citizen of the United States, residing at Logan, in the county of Hocking and State 5 of Ohio, have invented certain useful Improvements in Insulators, of which the following is a specification, reference being had therein to the accompanying drawing.

The invention relates to an insulator, and 10 more particularly to the class of wire retaining devices for insulators.

The primary object of the invention is the provision of a device of this character wherein an electric current wire can be securely fastened in the insulator and said wire can be readily removed when the occasion requires, the device being adaptable for use with various styles of insulators employed on cross arms or brackets for exterior electric wiring or on insulator knobs or cleats for interior construction of electric wiring.

Another object of the invention is the provision of a wire retaining device where 25 in the employment of nails, screws or other like fasteners is eliminated and the wire can be securely clamped in the insulator for holding said wire in place and is designed for use in supporting telephone or telegraph wires 30 for the distribution of electric current.

A further object of the invention is the provision of a wire retaining device of this character which is simple in construction, thoroughly reliable and efficient in use, 35 strong, durable, and inexpensive of manufacture.

Other objects will be in part obvious and in part hereinafter set forth.

The invention accordingly consists in the 40 features of construction, combination of elements and arrangement of parts which will be exemplified in the construction hereinafter described, and the scope of the application of which will be indicated in 45 the appended claims.

In the accompanying drawing:

Figure 1 is a vertical sectional view of an insulator, showing the wire retaining device in side elevation constructed in accordance with the invention applied;

Fig. 2 is a top plan view thereof;

Fig. 3 is a side elevation of the retaining cylinder of the device;

Fig. 4 is a perspective view of said retaining cylinder;

Fig. 5 is a side elevation of the bushing for the retaining cylinder supporting block.

Similar reference characters indicate corresponding parts throughout the several views of the drawing.

Referring to the drawing in detail, A designates generally an insulator body which is formed with a circular socket or recess 10 opening through the top thereof, while formed in the insulator body A at 60 diametrically opposite points in the wall of the recess 10 therein are wire receiving grooves 11 in which is adapted to be engaged an electric wire or wires, while mounted within the recess 10 is the wire 65 retaining device hereinafter fully described.

The wire retaining device comprises a block 12 preferably made from porcelain, although the same may be made from any other suitable insulating material and is 70 formed in sections, the block being retained in the recess through the medium of a securing bolt 13 which engages in the insulator body A as shown in Fig. 1 of the drawing.

The block 12 is preferably of rectangular shape and is formed with a wire receiving groove 14 which opens through the top of said block, and this groove is of curvilinear shape, with a flared or enlarged outer open 85 end, the grooves 11 in the insulator body being correspondingly shaped to the groove 14 in the block 12, and the electric wires are adapted to be engaged in said grooves and retained therein in a manner presently 90 described.

Formed medially of the block 12 is a seat 15 for receiving a rotary wire retaining cylinder 16 which, at the periphery thereof and centrally of the same, is formed with a rib 95 17 which engages in a channel 18 formed in the block 12, and this rib 17 engaging in said channel prevents lateral play of the cylinder 16 when rotated within the block. The cylinder 16 at one side is formed with 100 a longitudinally disposed notch 19 which opens through opposite ends of the cylinder and through the periphery thereof, the notch 19 being designed to receive the electric wire or wires therein, and on the rotation of the cylinder 16 in one direction the said wires will be brought into a position at the closed end of the grooves 11 and 14 in the insulator body A and block 12 therein for the retaining of the wire and the fastening of the same in the insulator.

Mounted within the channel 18 is a bushing 20 which receives the ribs 17 and prevents any strain upon the block 12, thereby

avoiding the fracturing of the block in the working of the wire retaining device.

In the cylinder 16 diametrically opposite the notch 19 is a notch 21 which is longitudinally disposed and opens through the opposite ends and periphery of said cylinder, and spanning this notch are normally outwardly bowed expanding webs 23 which, on the application of a tool such as pliers thereto, and the bending of the same in parallel relation to each other, will distort the cylinder to bind the same within the seat 15 therefor in the block 12 so as to prevent the working of the cylinder 16 outwardly from said seat.

Formed on and projecting laterally from opposite sides of the cylinder 16 at the periphery thereof are arms 23' formed with right angular legs or levers 24 which are disposed beyond opposite sides of the block 12, while formed on opposite side faces of the latter are cam swells 25 with which engage legs or levers 24 when the cylinder 16 has been rotated in one direction for the bringing of the electric wires to the inner ends of the grooves 11 and 14, and in this manner the cylinder is held fast in position for retaining the wires in said grooves. Thus it will be seen that the electric wires are retained within the insulator A and held fast by the retaining cylinder 16 which is locked in its retaining position when the legs or levers 24 on the arms 23' ride on to the swells 25 at opposite sides of the block 12 within the insulator.

It is of course to be understood that the wire retaining device can be mounted on or in various styles of insulators and different sizes of electric wires can be retained thereby for the fastening of the same in place. On reversing the rotation of the retaining cylinder 16 the wires can be readily removed or detached from the insulator, as will be obvious.

From the foregoing description, taken in connection with the accompanying drawing, the construction and operation of the herein described insulator will be readily apparent and, therefore, a more extended explanation has been omitted.

Having thus described my invention, I claim:

1. A wire retaining device comprising a member having a wire receiving groove therein, a wire retaining cylinder rotatably mounted within said member and having a notch for receiving a wire for delivering the same to the inner end of the wire receiving groove in the member on the rotation of said cylinder in one direction, and means on the cylinder and member for locking

said cylinder against accidental rotation in the reverse direction.

2. A wire retaining device comprising a member having a wire receiving groove 65 therein, a wire retaining cylinder rotatably mounted within said member and having a notch for receiving a wire for delivering the same to the inner end of the wire receiving groove in the member on the rotation of said cylinder in one direction, means on the cylinder and member for locking said cylinder against accidental rotation in the reverse direction, and a guide rib on the cylinder and engaged in the member. 70

3. A wire receiving device comprising a member having a wire receiving groove therein, a wire retaining cylinder rotatably mounted within said member and having a notch for receiving a wire for delivering the same to the inner end of the wire receiving groove in the member on the rotation of said cylinder in one direction, means on the cylinder and member for locking said cylinder against accidental rotation in the reverse direction, a guide rib on the cylinder and engaged in the member, and a bushing for said guide rib. 80

4. A wire retaining device comprising a member having a wire receiving groove 90 therein, a wire retaining cylinder rotatably mounted within said member and having a notch for receiving a wire for delivering the same to the inner end of the wire receiving groove in the member on the rotation of said cylinder in one direction, cam swells on opposite sides of the member, and arms on said cylinder and having levers for frictionally engaging with the cam swells to lock the cylinder in retaining position 95 for holding the wire at the inner end of the groove. 100

5. A wire retaining device comprising a member having a wire receiving groove therein, a wire retaining cylinder rotatably 105 mounted within said member and having a notch for receiving a wire for delivering the same to the inner end of the wire receiving groove in the member on the rotation of said cylinder in one direction, cam swells on opposite sides of the member, arms on said cylinder and having levers for frictionally engaging with the cam swells to lock the cylinder in retaining position for holding the wire at the inner end of the groove, and 110 expanding means in said cylinder and adapted to distort the same within the member to prevent the withdrawal thereof from the latter. 115

In testimony whereof I affix my signature. 120

CHARLES DISBENNET.
